UNITED STATES PATENT OFFICE

EDWARD R. KAST, OF PEARL RIVER, NEW YORK, ASSIGNOR TO DEXTER FOLDER COMPANY, OF NEW YORK, N. Y., A CORPORATION OF NEW YORK

SIGNATURE HANDLING MACHINE

Application filed August 5, 1929. Serial No. 383,578.

This invention relates to signature handling machines, and while capable of general use, is particularly adapted for association with a machine of this character, wherein the signatures are opened prior to delivery of the same onto the signature receiving device.

One object of the invention is to provide improved means for separating or opening the two halves of the signature prior to delivery of the same onto the receiving device.

Another object of the invention is to provide improved means for separating the two halves of the signature from each other, which may also be used to assist gravity in delivering the signature onto the receiving device.

Another object of the invention is to provide improved separating means adjustable to various positions so that an air blast or air blasts may be directed at any desired angle or angles onto the signatures to insure proper separation of the halves thereof and proper delivery of the signatures.

Another object of the invention is to provide improved air blast devices that are compactly and conveniently arranged and in which the air is controlled automatically in timed relation with signature opening and delivering devices.

Another object of the invention is to provide a simply constructed, highly efficient, and inexpensive separating means of this character.

These and other objects of the invention will appear as the following description thereof proceeds, and in order to more clearly understand said invention, reference may be had to the accompanying drawings which illustrate one embodiment of the inventive idea.

In said drawings—

Fig. 1 is an end elevation, partly in section, of a signature handling machine equipped with mechanism embodying the present invention;

Fig. 2 is an enlarged detail perspective view, with parts omitted, of the signature handling machine and associated devices illustrated in Fig. 1;

Fig. 3 is an enlarged end view, partly in

section, of said mechanism, showing nozzles positioned to direct blasts of air upwardly into open signatures delivered by gravity onto signature receiving means; and

Fig. 4 is a view similar to Fig. 3, showing said nozzles positioned to direct blasts of air downwardly onto the outer pages of open signatures as they drop by gravity onto said receiving means.

Referring to the drawings, wherein like reference characters designate like parts throughout the several views, the various movable parts of the machine therein illustrated are mounted on a framework that is indicated generally at 5 and bolted or otherwise suitably secured to the machine foundation 6. This framework includes the usual vertical legs 7 that have bolted or otherwise suitably secured to the tops thereof, supporting members 8 which extend longitudinally of the machine and carry at each end thereof a frame member 9. These frame members are connected together by supports 10 that extend longitudinally of the machine in parallel relation with the supporting members 8.

Mounted on the supports 10 at intervals along the same, are a series of signature hoppers, one of which is indicated generally at 11 (Fig. 1). Each of these hoppers is provided at the sides thereof with a plate 12, the bottom of the hopper being formed by rollers 13 and the front of the hopper being formed by vertical plates, one of which is indicated at 14. The back of the hopper is open, as clearly shown in Fig. 1, so that a stack of signatures 15 may be readily introduced into the hopper and supported therein by the rollers 13 and the plates 12 and 14.

Extending transversely of the machine and journaled in suitable bearings on the framework thereof, is a shaft 16 on which is fixed a pulley 17. The pulley 17 is driven by a belt 18 from any suitable source of power (not shown). Fixed on the shaft 16 is a bevel gear 19 that meshes with a similar gear 20 which is fixed on a shaft 21. This shaft 21 extends longitudinally of the machine and is journaled in suitable bearings on brackets, one of which is indicated at 22. These brackets

ets are bolted or otherwise suitably secured to the machine foundation 6, and the shaft 21 carried by said brackets constitutes the main driving shaft for the various movable parts of the machine.

5 Fixed on the shaft 21 is a gear 23 that meshes with a gear 24 which is fixed on a shaft 25. This shaft 25 extends longitudinally of the machine and is journaled in suitable bearings on the framework thereof. 10 Fixed on the shaft 25 is a gear 26 that meshes with a gear 27 which is fixed on a shaft 28. The shaft 28 extends longitudinally of the machine in parallel relation with the shafts 21 and 25 and is journaled in suitable bearings 15 on the frame 9 at each end thereof. The gear 27 meshes with a gear 29 that is fixed on a shaft 30 which also extends longitudinally of the machine in parallel relation with the shafts previously referred to. This shaft 20 30 is journaled in suitable bearings carried by brackets such as indicated at 31. These brackets are bolted or otherwise suitably secured to the supports 10 and extend transversely of the machine in spaced parallel 25 relation.

The shaft 30 has fixed thereon a cam (not shown) for imparting motion to a link 32 that is pivotally connected at 33 with the free 30 end of an arm 34. This arm 34 is fixed on a rockshaft 35 that is journaled in suitable bearings on the brackets 31. The shaft 35 also has fixed thereon an arm 36, to the free end of which is pivotally connected one arm 37 of a 35 bell crank. The other arm 38 of said bell crank carries a suction separator 39 which, through the described connections therefor with the cam on shaft 30, is moved up and down to engage the bottom signature of the stack and 40 separate the forward edge of said signature from those above it. The bell crank 37, 38 is pivoted at 40, on one of a series of brackets 41 that extend transversely of the machine and are bolted or otherwise suitably secured 45 to the supports 10 thereof. These brackets 41 carry the rollers 13 and other component parts of the signature hoppers above referred to.

As the forward edge of each signature is 50 separated by the member 39 said signature is seized by grippers 42, cam operated in any suitable manner, one toward the other, and carried by a rotatable support 43 that is fixed 55 on the shaft 30 to rotate therewith. These grippers, which act to separate the signature from the stack, carry the signature around and deposit it onto a table 44 provided with rollers 45 that feed the sheet or signature 60 down the table into the bite of a pair of suction rollers 46. These rollers are fixed on shafts 47 which extend longitudinally of the machine at the front thereof and are journaled in suitable bearings on brackets such as indicated at 47', said brackets being bolted

or otherwise suitably secured to the frame 9 and projecting outwardly therefrom as clearly shown in Fig. 1.

Referring more particularly to Fig. 2, it will be noted that a plurality of sets of rollers 46 are therein illustrated. The number of sets of rollers 46, as well as the number of separators 39, grippers 42, and feed tables 44, will correspond to the number of signature boxes, so that each of the latter is provided with means for separating, feeding, and delivering the signatures therein to a set of the rollers 46. The rollers 46 of each set, are driven in opposite directions, and for this purpose, the gear 27 meshes with a gear 48 80 that is fixed on one of the shafts 47. The shafts 47 have fixed thereon intermeshing gears 49, and it will thus appear that said shafts and the rollers 46 fixed thereon, are driven in opposite directions by the intermeshing gears 27, 48 and 49, 49.

The rollers 46 are hollow and provided in corresponding ends thereof with arcuate-shaped ports (not shown) adapted to intermittently register with the ends of suction 90 conduits 50 and thus intermittently create suction in said rollers. The ends of the conduits 50 which extend adjacent the rollers 46, are secured to disks 51 which are mounted on the shafts 47 and fixed against rotation therewith in any suitable manner. The conduits 50 are all connected with a suction pipe 52 which extends longitudinally of the machine and is supported in any suitable manner on the machine framework at the top and front 100 thereof. This pipe 52 is connected with a suitable source of suction (not shown) that creates a vacuum in the rollers 46 when the arcuate-shaped ports thereof are brought into register with the ends of the conduits 50. 105

The rollers 46 of each set are further provided at corresponding points thereon with apertured suckers 53 which are rotated into opposed relation when the signature is delivered edge downward between the rollers by the described feeding mechanism. At this time, the arcuate-shaped ports of the rollers are brought into registry with the ends of the suction conduits 50 and the vacuum thus created in the rollers 46 acts through the suckers 53 to separate the two halves of the signature as it is fed between said rollers for delivery onto a saddle to be presently described and which includes a signature conveyor. After the signature is thus opened, 115 the ports of the rollers 46 pass out of registry with the conduits 50 and the signature drops onto said saddle and conveyor. 120

The signature conveyor comprises an endless chain 54 provided at intervals therealong with signature pushing fingers 55. This chain passes over sprockets (not shown) which are mounted at opposite ends of the machine and driven in any suitable manner. The upper reach of the chain 54 is supported 130

on, and forms the upper part of, a saddle 56 which extends longitudinally of the machine below the rollers 46. This saddle 56, in turn, is supported on standards 57, each provided with an opening 58 for the lower reach of the chain 54. These standards are bolted or otherwise suitably secured to frame members, such as indicated at 59, said frame members being bolted or otherwise suitably secured, as at 60, to the machine foundation 6. It will of course be understood that when one set of rollers 46 delivers a signature onto the chain 54 in front of one of the pushers 55, said chain is moved forward below the next set of rollers which delivers a signature on top of the first mentioned signature. These operations are repeated to assemble the signatures in a manner well understood in the art and as shown in my Patent No. 1,236,181, granted August 7, 1917.

In accordance with the present invention, means are provided for delivering a blast or blasts of air into the signatures, in order to insure that the two halves thereof will be properly separated prior to delivery of the signature onto the saddle and the conveyor thereof. Said means will preferably be adjustable to direct the blast or blasts of air at the proper angle or angles with respect to the signature that is being opened by the rollers 46, and the embodiment of said means herein illustrated is preferably arranged and operated as follows.

Mounted between the rollers 46 and the signature assembling device comprised by the conveyor 54 and the saddle 56, are a plurality of nozzles 61, 62. These nozzles are disposed in inclined relation on opposite sides of the path of travel of the conveyor 54, and the opposed exit orifices of said nozzles, as shown in Fig. 3, are directed toward the rollers to deliver blasts of air into the signatures being opened thereby. The nozzles 61 are arranged in pairs under one roller 46 of each set thereof, and the nozzles 62 are likewise arranged in pairs under the opposite roller 46 of each set thereof. It was previously pointed out that the shafts 47 which carry said rollers are mounted in brackets 47' projecting from the front of the machine. These brackets have secured to or formed integrally therewith, lugs such as indicated at 63, and each of the nozzles 61 is gripped in a clamp 64 that is adjustably mounted at 65 on a holder 66. The holder 66, in turn, is mounted for vertical adjustment in a suitable opening in the corresponding lug 63 and retained in the desired position of adjustment therein, as by a set screw 67. Three adjustments for each nozzle 61 are thus provided, one being a vertical adjustment obtained by corresponding movement of the holder 66, the second being an angular adjustment obtained by swinging movement of the clamp 64, and the third a longitudinal adjustment of the nozzle

in said clamp. The nozzles 62 are each supported by a clamp 68 that is adjustably mounted at 69 in the slot 70 of a bracket 71 which is secured at 72 to the forward end of one of the brackets 47'. Three adjustments are thus provided for each nozzle 62, one being an angular adjustment obtained by swinging the clamp 68 about its pivot 69, the second being a vertical adjustment obtained by moving the clamp 68 along the slot 70 of bracket 71, and the third a longitudinal adjustment of the nozzle in said clamp.

The nozzles 61, 62 are connected with flexible conduits 73, 74, respectively. The conduits 73 are connected with elbows 77 which in turn are connected with pipes 75. These elbows are provided with manually operated valves 76 whereby the nozzles 61 may be thrown into or out of operation as desired. The conduits 74 are directly connected with the pipes 75, the conduits 74 being provided with manually operated valves 78 whereby the nozzles 62 may be thrown into or out of operation, as desired.

The pipes 75 extend longitudinally of the machine and are supported in any suitable manner on the frame work thereof. Said pipes are connected at 79 with valve casings 80 that are secured to or formed integrally with brackets 81 which are bolted or otherwise suitably secured at 82 to one of the supports 8. The valve casings 80 communicate through conduits 83 with a pipe 84 that is connected with a blower (not shown) for producing air blasts in the nozzles 61, 62. The control of the air blasts delivered through the nozzles 61, 62 is obtained by valves 85 which are slidably mounted in the valve casings 80 and operated through the medium of the following instrumentalities.

The gear 27 meshes with a gear 86 that is fixed on a shaft 87 and thus serves to drive the same. This shaft 87 extends longitudinally of the machine and is journaled in suitable bearings on the end frames 9 thereof. Fixed on the shaft 87 at intervals along the same, are cams 88 that engage rollers 89 which are journaled on links 90. These links 90 are provided with forks 91 that engage over the shaft 87, and said links are pivotally connected at 92 with the valves 85. The rollers 89 are maintained in engagement with the cams 88 by springs 93 that are mounted on rods 94. The opposite ends of said springs bear against the machine foundation 6 and collars 95, said collars being secured on the rods 94 by machine screws 96 or the like. The upper ends of the rods 94 are pivotally connected at 97 with the valves 85 and the links 90. The lower ends of the rods 94 extend freely in suitable openings 98 formed in the machine foundation 6.

The operating mechanism for the valves 85 is so timed with respect to the operating mechanism for the rollers 46, that when the

signatures are fed between the latter and opened, blasts of air will be directed by the nozzles between the opened parts of the signatures.

It will of course be understood that when the signatures are released from the rollers 46 for delivery onto the conveyor 54, the valves 85 will be closed to cut off the air blasts through the nozzles 61, 62.

10 The nozzles 61, 62 may, by the described adjustments therefor, be moved to various positions in order to obtain a direction and effect of the air blasts best suited to the signatures being handled in the machine.

15 In the event that signatures with uncut or folded edges are handled in the machine, the nozzles 61, 62 could be alternately thrown out of operation by the valves 76, 78, respectively, in accordance with the location of the uncut edges with respect to the saddle 56. In Fig. 3, for example, the uncut edge of the signature 15 there shown is disposed over the left side of saddle 56, in which case the nozzles 62 would be thrown out of operation by 20 closing the valves 78. On the other hand, if the uncut edge of the signature was disposed over the right side of saddle 56, the nozzles 61 would be thrown out of operation by closing the valves 76. The nozzle under the 25 roller that is engaging the closed or folded half of the signature is the one that is used, and it is aimed or directed to deliver the blast against the half of the signature having open edges in order to insure that none of the 30 leaves of the half of the signatures having open edges shall be deposited on the wrong side of the saddle.

Further, on four page signatures, for example, where no trouble is encountered in 40 opening the same and the machine is running at high speed, the air blasts on both sides of the saddle can be used to assist gravity in delivering the signatures onto the receiving means or saddle. In this case, the 45 nozzles 61, 62 would preferably be turned downwardly to the positions thereof shown in Fig. 4, so as to direct the air blasts onto the outer pages of the signatures.

In the event signatures with cut edges on 50 both halves thereof are handled in the machine, the signatures will preferably be opened at one side by mechanical gripper that grips one half of each folded signature. The nozzle arranged under the opening roller or cylinder provided with the grippers will be 55 employed, and so positioned as to blow air against the other half of the signature to keep it on the proper side of the saddle.

It will be noted that the air is delivered 60 through the nozzles 61, 62 intermittently, rather than continuously. Continuous air blasts sometimes blow the signatures off the receiving means or saddle. This difficulty is eliminated by the present invention through 65 the provision of means for timing the air

blasts with respect to rotation of the rollers and the making and breaking of suction therein, the air being delivered through the nozzles when the signatures are in position for delivery onto the saddle, and being cut off just as the signatures are dropped onto the saddle.

70 While one embodiment of the inventive idea is herein disclosed and described with more or less particularity, it is to be expressly understood that the invention is not limited to such embodiment, or otherwise than by the terms of the appended claims.

75 What is claimed is:

1. In a machine of the character described, 80 a signature receiving device, a pair of members for opening and delivering a signature onto the signature receiving device, and one or more inclined nozzles adapted to direct a blast or blasts of air onto said signature when it is opened by said members.

2. In a machine of the character described, 85 a saddle, a pair of members for opening and delivering a signature onto said saddle, and a pair of nozzles inclined toward each other and each adapted to direct a blast of air onto 90 said signature.

3. In a machine of the character described, 95 a signature conveyor, a pair of rollers for opening and delivering a signature onto the signature conveyor, and a plurality of inclined nozzles having opposed exit orifices each adapted to discharge a blast of air onto said signature.

4. In a machine of the character described, 100 a saddle, means for opening and delivering a signature onto the saddle, and nozzles at opposite sides of the saddle and each adapted to direct a blast of air onto said signature.

5. In a machine of the character described, 105 a signature receiving device, a plurality of sets of elements for opening and delivering signatures thereto, and a plurality of means each disposed adjacent one of said sets of elements and adapted to direct a blast or 110 blasts of air onto said signatures.

6. In a machine of the character described, 115 a signature receiving device, means for opening and delivering a signature thereto, and a nozzle interposed between the signature receiving device and said means and adapted to direct a blast of air onto the signature when it is opened by the latter.

7. In a machine of the character described, 120 a signature receiving device, means for opening and delivering a signature thereto, a nozzle adapted to direct a blast of air onto the signature when it is opened by said means, and means for adjusting said nozzle to various positions.

8. In a machine of the character described, 125 a signature receiving device, means for opening and delivering a signature thereto, a nozzle for directing a blast of air onto the signature between said device and said means,

- and supporting means for said nozzle providing for adjustment of the same angularly and rectilinearly.
9. In a machine of the character described, a signature conveyor, means for opening and delivering a signature thereto, nozzles at opposite sides of the path of travel of the signature conveyor and adapted to direct blasts of air onto the signature, and supporting means for said nozzles providing for adjustment of the same angularly and rectilinearly.
10. In a machine of the character described, a signature receiving device, means for opening and delivering a signature thereto, a nozzle adapted to direct a blast of air onto the signature, and automatically operated means for controlling the delivery of the air through said nozzle.
11. In a machine of the character described, a signature receiving device, means for opening and delivering a signature thereto, a nozzle adapted to direct a blast of air onto the signature, a valve for controlling the delivery of the air through said nozzle, and operating mechanism for said valve.
12. In a machine of the character described, a signature assembling device, a plurality of sets of elements for opening and delivering signatures onto the signature assembling device, a plurality of means each disposed adjacent one of said sets of elements and adapted to direct a blast or blasts of air onto the signature opened thereby, a plurality of valves each adapted to control the delivery of air through one of said means, and operating mechanism for said valves.
13. In a machine of the character described, a signature receiving device, means for opening and delivering a signature thereto, a nozzle adapted to direct a blast of air onto said signature, an air conduit connected with the nozzle, a valve in said conduit controlling the delivery of air through the latter and said nozzle, and mechanism for operating said valve.
14. In a machine of the character described, a signature conveyor, means for opening and delivering a signature thereto, nozzles at opposite sides of the path of travel of the signature conveyor and each adapted to direct a blast of air onto said signature, an air pipe, conduits connecting said pipe with said nozzles, automatically operated valve mechanism controlling the delivery of air through the pipe, conduits, and nozzles, and manually operated valves for selectively controlling the delivery of air through said nozzles as desired.
15. In a machine of the character described, signature opening and delivering means, a device adapted to receive an opened signature therefrom, and means for directing air onto the opened signature to insure proper delivery of the signature onto said device from said opening and delivering means.
16. In a machine of the character described, a signature receiving device, means for opening and delivering a signature thereto, and means for directing air onto said signature between said means and said device.
17. In a machine of the character described, signature opening and delivering means, a device adapted to receive an opened signature therefrom, and means for directing air selectively onto one side or the other of the opened signature to insure proper delivery of said signature onto said device from said opening and delivering means.
18. In a machine of the character described, a signature receiving device, means for opening and delivering a signature thereto, and means for directing air onto the signature selectively from opposite sides of said means and between the latter and said device.
19. In a machine of the character described, signature opening and delivering means, a device adapted to receive an opened signature therefrom, means for directing air onto the signature between the opening and delivering means and said device, and automatically operated means controlling the delivery of air through said air directing means.
20. In a machine of the character described, signature moving means, a plurality of means adapted to open and deliver signatures onto the signature moving means, and a plurality of means adapted to direct air onto the signatures between the opening and delivering means and said signature moving means.
21. In a machine of the character described, signature moving means, a plurality of means adapted to open and deliver signatures onto the signature moving means, a plurality of means for directing air onto the signatures between the opening and delivering means and said signature moving means, and automatically operated means controlling the delivery of air through said plurality of air directing means.
22. In a machine of the character described, signature moving means, a plurality of means adapted to open and deliver signatures onto the signature moving means, and a plurality of means for directing air onto the signatures selectively from one side or the other of said signature moving means.
- In testimony whereof I have signed this specification.
- EDWARD R. KAST.
